UNITED STATES PATENT OFFICE

DONALD B. TOLLEY, OF MACOMB, ILLINOIS, ASSIGNOR TO AMERICAN STEEL PRODUCTS CO., OF MACOMB, ILLINOIS, A CORPORATION OF ILLINOIS

ELECTRICALLY HEATED BROODER

Application filed November 26, 1928. Serial No. 222,054.

My invention relates to electrically heated brooders for chicks; and in its general objects aims to provide an electric brooder which will require no perforated floor under it, which will not overheat the floor, which will insure an adequate movement of air to prevent a "sweating" of the chicks, which will neither subject the chicks to strong air drafts nor permit them to contact with unduly hot brooder portions, which will be efficient in proportion to the heat developed by the electric heating member, which will hold the heat for a considerable period of time after the current is shut off, which will fairly equalize the temperature throughout the brooder chamber, and in which the rate of air movement can readily be controlled from outside the brooder.

More particularly, my invention aims to provide an electric brooder which utilizes both radiation and convection as the means of distributing the heat of the heating member through the brooder, and one in which a relatively flat metal hover can be employed without an undue loss of heat by conduction from this hover to the outer air. It also aims to provide a double-shelled convection-producing arrangement so disposed with respect to the heating member that the air moving through it will cool the outer shell, thereby preventing an undue heating of the central portion of the brooder chamber. It also aims to provide an electric brooder of these characteristics which will be inexpensive in construction and which can readily be tipped up as a unit for cleaning both the brooder and the floor under it.

Still further objects will appear from the following specification and from the accompanying drawings, in which

Fig. 1 is a fragmentary central and vertical section through an electric brooder embodying my invention.

Fig. 2 is an enlarged perspective view of the air drum unit of this brooder, showing this unit before it is attached to the heat-deflecting and heat-conducting hover of the brooder.

Fig. 3 is an enlarged and fragmentary plan view of my brooder, with a portion of

the canopy broken away to show two of the ports which connect the brooder chamber with the upper air chamber.

Fig. 4 is an enlargement of a portion of Fig. 1, showing the fastening of the drum unit portions to each other and to the heat-insulated hover.

Fig. 5 is an enlarged and fragmentary vertical section taken along the line 5—5 of Fig. 3.

In the illustrated embodiment, my unitary electric brooder includes a plurality of legs 1 underhanging edge portions of a hover or heat deflector 2, which heat deflector preferably is of a relatively flat conical shape so as to slope slightly upwards toward the axis of this heat deflector. This hover or heat deflector 2 forms the top of the brooder chamber, while curtains 18 depending from a wire 3 supported by clips 19 near the edge of the heat deflector form the peripheral wall of this chamber.

Mounted in the center of this hover 2 is a socket 4 for a detachable electric heater 5 which has its heating portion disposed axially of the hover and at a considerable height above the floor. This electric heater may be of varying types, but desirably is of a form in which the electrically heated portion (such as a coiled high resistance wire) is distributed with substantial uniformity around the vertical axis of the heater.

Surmounting the hover 2 is a canopy which preferably has a downwardly flaring frustoconical wall 3 supported at its edge by the hover or heat deflector 2, the wall 3 being of sharper angled conical formation than the said deflector, so as to afford a chamber 6 of considerable height above the heat deflector.

The top 7 of the canopy is desirably horizontal, and this top may support a socket 8 for a lamp bulb 9 exposed above the brooder and connected in circuit with the electric heater to serve as a pilot light for indicating whether or not current is being supplied to the electric heater.

The brooder chamber under the heat deflector is connected to the air chamber 6 by ports 10 in the hover near the periphery of

the latter, and this air chamber has air outlet ports 11 which desirably are in the central portion 7 of the canopy, so that the warm air in passing through the air chamber will have

- 5 to follow tortuous paths. To prevent an undesirable passage of heat from the brooder chamber to the interior of the air chamber by conduction through heat deflector 2, which desirably is of sheet metal, I cover this hover
10 with a layer 20 of a suitable heat-insulating material, such as a board made of sugar cane fibre, and extend the ports 10 through this heat insulation.

Disposed within the brooder chamber, and 15 desirably suspended from the hover 2, is a drum unit which serves the four-fold purpose of affording air circulation in effective directions within the brooder chamber, of guarding the chicks from contact with any unduly 20 hot portion of the brooder, of shielding the chicks against direct radiation from the electric heater at close range, and of preventing this heater from overheating the floor under it.

- 25 This drum unit (shown separately in Fig. 2) comprises an imperforate and upright outer drum 13 suspended by straps 24 from the hover, and an inner drum 14 extending below the bottom of the inner drum and fitted with a bottom 15 of heat-insulating material. The inner drum is held in concentric relation to the outer drum by radial spacer arms 25 which desirably form extensions of the straps 24, so that the inner drum is also 30 supported by these straps.

Air is admitted to the inner drum by ports 17 above and near its heat-insulating bottom 15, and the total height of the drum unit is preferably such that, with the straps 24 secured at their upper ends to the hover, the bottom of the inner drum will be somewhat above the floor 26 on which the legs 1 rest, thereby allowing for warping or other irregularities in the floor.

- 40 45 When current is supplied to the electric heater, the warming of the adjacent air by it will cause a strong upward air movement within the inner drum 14, thereby drawing relatively cool air in to this drum through the inlet ports 17 and causing this air to pass laterally of the electric heater when issuing from the top of this inner drum, as shown by the dotted line A in Fig. 1. This heated air then spreads radially along the lower face of 50 55 the heat deflector 2, and a little of the hot air will pass through the ports 10 into the air chamber 6.

The heat deflector 2 is also heated by direct radiation from the heating member, so that 60 this heat deflector serves to redirect rays from the heating member downward outwardly of the brooder, as indicated at B in Fig. 1. Being of metal, this heat deflector also conducts heat readily from its center toward its outer edge, thereby forming a warm heat-radiat-

ing top for the brooder chamber and assisting the air currents towards fairly equalizing the temperature throughout the brooder chamber.

At least one of the drums desirably extends 70 upwards beyond the lower end of the heating member so as to shield the chicks (when near the drums) from the direct rays radiated by the heating member.

The flow of heated air from the top of the 75 inner drum radially outward over the annular air space between the two drums also tends to draw air upward through the said air space, and this tendency is increased by convection owing to the warming of the air in 80 this space by conduction of heat through the metal of the inner drum 14. Consequently, there is a continuous upward movement of air through the said annular space (as indicated at C in Fig. 1) and this air moves 85 radially outward under the heat deflector 2 so as to be warmed also by radiation of heat from the latter. This air movement not only enhances the general circulation of air within the brooder chamber, but also keeps the 90 outer drum 13 at a considerably lower temperature than the inner drum 14, so that the chicks will not be scorched by contact with the outer drum.

Furthermore, since the continually replenished air in the space between the two drums is heated by direct radiation from the hot inner drum, the outer or guard drum never approaches the inner drum in its temperature. Consequently, the outward radiation 100 of heat from the outer drum 13 is small, so that I avoid having an intensely heated central portion (or "hot spot") in my brooder chamber, such as would be present if only the inner drum or shell were employed around 105 the heating member. Thus my double drum or shell arrangement serves the threefold purpose of compelling the air to circulate, guarding the chicks against scorching, and avoiding a relatively high temperature in the 110 radially inner portion of the brooder chamber.

The heat-insulation 20 prevents any considerable conduction of heat from the heat deflector 2 to the air chamber 6, thereby conserving the heat for the brooder chamber which is only moderately warmed by the relatively small amount of air passing through the ports 17. This chamber 6 also affords a convenient place for a thermostatic switch 115 if one is used for controlling the current, as a switch when disposed in this chamber is housed against tampering or accidental injury and does not encumber the brooder chamber. (Since suitable switches and their 120 connections are commonly known, none has been shown in the drawings).

To control the rate at which air passes through the upper air chamber 6, I preferably provide means for controlling the out- 130

let ports 11, as for example a rotatable damper 28. This damper can be wide open when the current for the heating member is first turned on, but may be partly closed later on, so as to throttle the air movement and confine warmed air longer in the air chamber. The total area of the ports 10 leading from the brooder chamber under the heat deflector to the air chamber is preferably much smaller than the total area of the inlets of the two drums, so that only a quite small portion of the heated air rising through these drums will pass direct into the air chamber. The remaining and by far larger portion of the warmed air recirculates within the brooder chamber and there intermingles with the small amount of fresh air which is drawn into the brooder chamber through the spaces under or between the curtains. Consequently, I secure a constant circulation of air throughout the brooder chamber and a continuous freshening of this air, both of which are important for the welfare of the chicks.

To reduce the conduction of heat from the hover to the canopy, I desirably have these parts contact only at their edges, leaving them otherwise freely spaced, so that the upper chamber forms an efficient air jacket for cooperating with the insulating covering of the hover in reducing losses of heat. Since this air chamber stores warm air and since the curtains 18 afford lateral heat insulation, my electric brooder will retain an ample warmth for considerable periods of time after the current is turned off, if the damper is closed, thus increasing the economy which can be effected by the use of an automatic (thermostatic) switch.

The air circulation effected by my drum unit also permits me to use a heat-deflecting hover of large conical angle and hence of low height, thus cooperating with the above described movements of the air to prevent all banking of hot air in the apex of the hover, so that I can secure the desired temperature with ample uniformity of distribution in a relatively quite low and compact brooder.

Moreover, the use of such a relatively flat heat-deflector enables me to reduce the total volume of air in the brooder chamber in proportion to its floor area, thus securing a large heating effect in proportion to the wattage of the electric heating member, and the low average height of the heat deflector increases the effectiveness of the heat radiated downwardly by it.

By suspending the drum unit from the hover I not only insure an axial alining of the drums with the heating element but also make the entire hover a unit which can be tipped up on edge or inverted for ready access to all of the parts below the hover, thereby making it easy for the user to keep the brooder in a clean and highly sanitary condition.

I claim as my invention:

1. In a brooder, a heat deflector, means for supporting the deflector at an elevation above a floor, a heater supported below and near the center of the deflector; and a drum unit suspended from the deflector above the floor and in axial alinement with the deflector; the drum unit comprising as a rigid assembly two concentric and freely spaced upright drums each open at its upper end, spacer elements radially spacing the two drums, means for suspending the drums from the deflector, and a closure of heat-insulating material for the lower end of the inner drum; the outer drum being freely open at its lower end and having its lower end freely spaced from the floor and curtaining depending from the outer edge of the deflector, the space between the curtaining and the outer drum below the deflector being unobstructed.

2. In a brooder, a metallic heat deflector having an effectively imperforate central portion, means for supporting the deflector at an elevation above the floor; a canopy above the deflector having its edge secured to the edge of the deflector, the canopy being otherwise freely spaced from the deflector to afford an air chamber therebetween; the deflector having ports near its outer edge leading to the said chamber from the space below the deflector; the canopy having upper outlet ports; a heater supported by and depending from the center of the deflector; and air confining means suspended from the deflector and adjacent to the heater for causing air warmed by the heater to rise in a hot central stream and in a less warmed annular stream surrounding the central stream and merging with the latter adjacent to the said central portion of the deflector.

3. A brooder comprising a relatively flat heat deflector, legs supporting the heat deflector at an elevation above the floor and with the outer edge of the deflector horizontal, an electric heater depending from the center of the deflector, a cup-shaped air directing member suspended from the deflector coaxial with the deflector and provided with relatively low air inlets and having its upper end freely spaced from the deflector; an imperforate tubular and upright guard of larger diameter than the cup-shaped member and concentric with the latter and arranged for admitting air at its bottom to the space between the guard and the said cup-shaped member, the guard being spaced at its upper end from the deflector; curtaining depending from the edge of the deflector for retarding the entrance of air into the space below the deflector, and an air chamber above the deflector; there being inlet ports radially outward of the said guard for admitting air from the said space to the air chamber and outlet ports in the top of the air chamber, the total area of the said inlet ports

being such as to admit air to the air chamber at a much lower rate than that at which air is admitted to the cup-shaped member and to the space between the latter and the guard.

- 5 4. A brooder comprising a heat deflector, means for supporting the deflector at an elevation above a floor, a top cooperating with the heat deflector to form an air chamber above the heat deflector, an electric heater below the heat deflector; and two upright and radially spaced drums having a common axis in substantially vertical alinement with the axis of the electric heater, each drum having its upper end spaced from the heat deflector and both drums being formed for admitting air from near the floor; the heat deflector being provided near its periphery with inlet ports connecting the said chamber with the space below the heat deflector, and the air chamber having air outlets in its top and out of vertical alinement with the said inlet ports.
